UNITED STATES PATENT OFFICE

HARRY MAURUS, OF NEW YORK, N. Y., ASSIGNOR TO DUPLAN SILK CORPORATION, OF NEW YORK, N. Y., A CORPORATION OF DELAWARE

DESIGN FOR A TEXTILE FABRIC

Application filed May 28, 1930. Serial No. 35,806. Term of patent 8½ years.

To all whom it may concern:

Be it known that I, HARRY MAURUS, a citizen of the United States, residing at 102 West 93rd Street, city, county, and State of New York, whose post-office address is 135 Madison Avenue, city, county, and State of New York, aforesaid, have invented a new, original, and ornamental Design for a Textile Fabric, of which the following is a specification, reference being had to the accompanying drawing, forming part thereof.

The figure is a plan view of a textile fabric showing my new design.

A single unit of my design is substantially comprised within the area defined by the indicating lines shown on the drawing which unit is repeated over the surface of the fabric in the relation indicated.

I claim:

The ornamental design for a textile fabric substantially as shown and described.

HARRY MAURUS.
